UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed November 19, 1925. Serial No. 69,954.

This invention relates to fluid actuated rock drills, but more particularly to a distributing valve for drills of this type.

The objects of this invention are to enable

5 an oscillatory distributing valve of the plate type to be suitably mounted in a cylindrical bore, to protect the valve chest against wear, and to simplify the construction and reduce the manufacturing cost of valves of this 10 type.

Other objects will be in part obvious and in part pointed out hereinafter.

The invention consists of the combinations 15 of elements, features of construction and arrangement of parts having the general mode of operation substantially as herein-after described and more particularly pointed out in the appended claims and 20 illustrated in the accompanying drawings, in which—

Figure 1 is an elevation in section of so much of a rock drill as will serve to illustrate the invention and showing the valve and the piston in one position.

25 Figure 2 is a view similar to Figure 1 and showing the valve and the piston in another position.

Figure 3 is a transverse view in section taken through Figure 1 on the line 3—3 30 looking in the direction of the arrows,

Figure 4 is a perspective view of the valve, and

Figure 5 is an end view of the valve.

Referring to the drawings, the invention 35 is shown embodied in a rock drill having a cylinder A provided with a free exhaust port B. Within the cylinder A is a reciprocating hammer piston C having a forward extension or nose D. In this instance the cylinder A is sealed at its front end by a head E which receives slidably the nose D of the piston C and the rearward end of the cylinder A is provided with a closure in the form of a back head F.

45 The parts so far described are shown merely for illustrative purposes, according- ly, the back head F is shown solid.

In accordance with the present invention, the valve chest G, preferably formed integrally with the cylinder A and longitudinally thereof is provided with a cylindrical bore H. An end wall J in this instance forms a closure for one end of the bore H and the opposite end of said bore is screw threaded 50 as at K to receive a suitable sealing plug L

which may be provided with a slot O for the reception of a screw driver or other suitable instrument whereby the plug may be screwed into the end of the bore H.

Within the cylindrical bore H in this instance is arranged a filler piece or valve seat P having passages Q and R near the front and rear ends thereof. The passages Q and R communicate with passages S and T leading to the front and rear ends of the cylinder A for the admission of pressure fluid to said cylinder for reciprocating the piston C. The valve seat P is preferably of partly circular or, as illustrated, of semi-circular cross sectional area and accordingly has a semi-cylindrical surface U to cooperate with the cylindrical wall of the bore H. The valve seat P in this instance is also provided with a flat surface V which serves as a seating surface for an oscillatory plate valve W. 75

The oscillatory plate valve W is preferably of a length approximately equal to the length of the stroke of the piston C plus the length of the head of said piston and is provided intermediate its ends and on its top face with a bridge X which cooperates with the roof of the bore H for holding the seating portion of the valve W on its seat. Surfaces Y and Z of the valve W which control the passages R and Q respectively are in 85 this instance formed at an angle to each other so that when one surface Y or Z contacts with the surface V of the seat P, the other surface Y or Z will be raised from the surface V at an angle equal to the angle of the surface Y to the surface Z.

Suitable common means are provided for holding the valve seat P and the valve W in operative position with respect to each other. To this end the valve seat P is provided with a transverse semi-circular slot b to receive slidably a pin c anchored at its ends in the valve chest G as shown at d in Figure 3. A transverse partly circular slot e, somewhat similar to the slot b, is formed 90 through the valve W to cooperate pivotally with the pin c whereby the valve W is held against longitudinal movement. The slot e is of slightly greater depth than the slot b so that a clearance exists between the top 105 of said slot and the pin c. In this way the valve W contacts only with the pin c at the entrance of the slot e.

Pressure fluid for operating the drill may be supplied to the bore H through a connec- 110

tion *f*. In this instance a pair of passages *g* and *h* afford communication between the connection *f* and the cylindrical bore *h*.

In the operation of the rock drill: Let it be assumed that the piston is about to start on its forward stroke as indicated in Figure 1. The front end of the cylinder *A* will then be open to the atmosphere through the exhaust port *B*. In this position of the piston 10 ton, pressure fluid admitted into the cylindrical bore *H* will force the front end of the valve *W* down on the surface *V*. The rearward end of the valve will then be raised as illustrated in Figure 1 to admit pressure fluid through the passages *R* and *T* into the rearward end of the cylinder *A* and impel the piston *C* forwardly. After the free exhaust port *B* in the cylinder *A* is covered by the piston *C*, atmospheric air entrapped 20 in the forward end of the cylinder will be compressed and will act against the surface *Z* of the valve *W* tending to unseat the front end of the valve. As the piston nears the end of its forward stroke, the exhaust port 25 *B* will again be uncovered by the rearward end of the piston and pressure fluid utilized for impelling the piston forwardly will be exhausted through said exhaust port to the atmosphere. Owing to the drop in pressure 30 thus obtained beneath the rearward end of the valve, the pressure fluid acting on top of said rearward end, augmented by the compression acting against the front end of the valve will rock the valve about the pin 35 *c* so that the rearward end of the valve is pressed downwardly against the face *V* to close the passage *R* leading to the rearward end of the cylinder *A*. In this position of the valve, pressure fluid will flow over the 40 front end of the valve and through the passages *Q* and *S* into the front end of the cylinder and impel the piston *C* rearwardly, thus completing the cycle of operations.

By pivoting the valve *W* on the pin *c* in 45 the manner described, a shifting fulcrum will be obtained, that is, the valve surface exposed to reduced pressure during the operation of the valve varies with the position of the valve. This is illustrated in Figure 50 1, in which only the surface *Z* of the valve rests on the surface *V* of the valve seat *P*. In this position of the valve, the combined areas of the surface *Y* and of the slot *e* are raised from the surface *V* of the seat *P*. 55 After the piston *C* has travelled forwardly to permit the rearward end of the valve *W* to be rocked against the surface *V*, the surface *Z* and the slot *e* will be raised from the valve seat.

The advantages of this invention reside 60 chiefly in the fact that an oscillatory valve of the plate type may be mounted in a cylindrical bore. This is a distinct advantage over methods employed heretofore for mounting valves of this type.

Usually in drills employing oscillatory plate valves, square or rectangular valve chambers are provided. Such construction is not only expensive but also prevents the valve chest from being formed integrally 70 with the cylinder, thus adding greatly to the cost of the drill. By means of the construction described heretofore, the valve chamber may be quickly and economically formed to receive the valve and its seat, the valve parts 75 may be quickly assembled or disassembled and the valve chest *G* will be protected against any wear which might otherwise be caused by the valve *W* were the valve allowed to come in direct contact with the 80 chest.

In the drawings, the valve seat *P* is illustrated as being equal to the length of the unthreaded portion of the bore *H* so that the outer end of the valve seat *P* is shown as contacting with the plug *L*. If desired, however, the valve seat *P* may be shortened somewhat so that it will be out of contact with the parts adjacent said ends.

I claim:

1. In a fluid actuated rock drill, the combination of a cylinder and a reciprocatory piston, a free exhaust port in the cylinder controlled by the piston, a valve chest having a cylindrical bore, an oscillatory plate valve in the bore, a removable valve seat seated on the cylindrical wall of the bore, and common means for holding the valve and the valve seat in operative position.

2. In a fluid actuated rock drill, the combination of a cylinder and a reciprocatory piston, a free exhaust port in the cylinder controlled by the piston, a valve chest having a cylindrical bore, an oscillatory plate valve in the bore, a removable valve seat seated on the cylindrical wall of the bore, and common means extending through adjacent faces of the valve and the valve seat for holding said valve and said valve seat in operative position.

3. In a fluid actuated rock drill, the combination of a cylinder and a reciprocatory piston, a free exhaust port in the cylinder controlled by the piston, a valve chest having a cylindrical bore, an oscillatory plate valve in the bore, a removable valve seat in the bore and having a surface to cooperate with the cylindrical wall of the bore, and a pin extending through the valve chest and through the valve and the valve seat to serve as a pivot for the valve and to hold the valve and the valve seat in operative position.

4. In a fluid actuated rock drill, the combination of a cylinder and a reciprocatory piston, a free exhaust port in the cylinder controlled by the piston, a valve chest having a cylindrical bore closed at one end, an oscillatory plate valve in the bore, a removable valve seat in the bore and having a sur-

face to cooperate with the cylindrical wall of the bore, said valve and said valve seat being insertable through the open end of the bore, a plug for closing the open end of the bore, and a pin cooperating with the valve and the valve seat for holding said valve and valve seat in operative position.

5. In a fluid actuated rock drill, the combination of a cylinder and a reciprocatory piston, a free exhaust port in the cylinder controlled by the piston, a valve chest having a cylindrical bore, a removable valve seat occupying one side of the bore and seated on the cylindrical wall of the bore, a 10 pin extending through one side of the valve seat for holding said valve seat in position, an oscillatory plate valve pivoted on said pin and held against endwise movement by said pin, and a bridge on said valve to 15 operate with the bore for holding the valve on said pin.

6. In a fluid actuated rock drill, the combination of a cylinder and a reciprocatory piston, a free exhaust port in the cylinder controlled by the piston, a valve chest having a cylindrical bore, a removable valve seat occupying one side of the bore and having a partly circular surface to seat on the wall of the bore and a flat surface, an oscillatory plate valve on said flat surface, and a pin extending through adjacent faces of the valve and the valve seat for holding said valve and said valve seat in operative position and to serve as a pivot for the 35 valve.

7. In a fluid actuated rock drill, the combination of a cylinder and a reciprocatory piston, a free exhaust port in the cylinder controlled by the piston, a valve chest having a cylindrical bore, a removable valve seat occupying one side of the bore and having a partly circular surface and a flat surface, an oscillatory plate valve on said flat surface, a pin extending through adjacent faces of the valve and the valve seat for holding said valve and said valve seat

in operative position and to serve as a pivot for the valve, and a bridge on one side of the valve to cooperate with the bore for holding said valve on the pin.

50

8. In a fluid actuated rock drill, the combination of a cylinder and a reciprocatory piston, a free exhaust port on the cylinder controlled by the piston, a valve chest having a cylindrical bore, a removable valve seat occupying one side of the bore and having a partly circular surface and a flat surface, passages through the valve seat for supplying pressure fluid to the ends of the cylinder, an oscillatory plate valve on said flat surface for controlling said passages, a pin insertable transversely through the valve chest to extend through the valve and the valve seat for holding said valve and valve seat in operative position and to serve as a 60 pivot for the valve, and a bridge on one side of the valve to cooperate slidably with the bore for holding the valve on the pin.

65

9. In a fluid actuated rock drill, the combination of a cylinder and a reciprocatory piston, a free exhaust port in the cylinder controlled by the piston, a valve chest having a cylindrical bore extending longitudinally of the cylinder, a semi-circular removable valve seat occupying one side of the 70 bore and having a flat surface, said valve seat having passages through its ends leading to the ends of the cylinder, a plate valve adapted to oscillate on said flat surface for controlling the passages, slots transversely through adjacent faces of the valve and the valve seat, a pin extending through the slots and anchored at its ends in the valve chest for holding said valve and valve seat in 75 operative position and to serve as a pivot for the valve, and a bridge on one side of the valve to cooperate with the wall of the bore for holding the valve on the pin.

80

In testimony whereof I have signed this 85 specification.

CHARLES C. HANSEN.
